HAROLD PICKARD, HARRY PICKARD, AND NORMAN PICKARD, OF BLACKPOOL,
ENGLAND

AMUSEMENT DEVICE

Application filed February 16, 1931, Serial No. 516,228, and in Great Britain September 27, 1929.

This invention relates to amusement devices of the class comprising, briefly, a staging for supporting conveyors which carry cars whereby passengers are elevated until they reach the top of the staging whereupon the cars are tilted and thereby eject the passengers into chutes down which they slide back to the starting point.

The objects of this invention are, briefly, to provide improved means for the following purposes:—to right the cars after discharge of the passengers therefrom; to facilitate the reversal of direction of travel of the cars after discharge of the passengers; to connect the cars to the conveyors; to prevent friction on the hands and arms and clothing of the passengers as they slide down the chutes; and to gradually reduce the speed of the passengers at the discharge end of the chutes.

In the drawings,

Figure 1 is a broken side elevation of a double amusement chute in accordance with this invention,

Figure 2 is a plan of Figure 1.

Figure 3 is a plan of a single amusement chute in accordance with this invention.

Figures 4 and 5 show in end elevation and side elevation respectively, the car and its connection to the conveyor.

Figures 6, 7 and 8 show various devices which may conveniently be adopted for facilitating the return of the car at the top of the conveyor.

Figure 9 shows the chute in cross-section.

In the drawings, *a* is the staging, *b*, *b* are the conveyors, *c*, *c* are the cars, and *d*, *d* are the chutes. The conveyors comprise endless chains which pass over sprockets *e*, *e*.

In the apparatus shown in Figures 1 and 2, the conveyor, cars and chute on one side are duplicated on the other side, so for convenience of description they will generally be hereinafter referred to in the singular number.

Appropriate links of the conveyor chains have fixed thereto short lengths of L-bar *b*¹ (see Figures 4 and 5), through the webs of which are formed holes *b*² which are countersunk on opposite sides and as shown in broken lines in Figure 4, *c*¹ is a transversely arranged

pivot shaft which is fixed in the front legs *c*² of the car and passes snugly through the hole *b*² in the bar *b*¹ between which latter and the inner sides of the legs *c*² are arranged compression springs *c*³ encircling the shaft *c*¹. The rear legs *c*⁴ of the car are connected together by a tie *c*⁵, and mounted in the lower ends of the rear legs are axles *c*⁶ carrying skids or wheels *c*⁷ which run, during the ascent of the cars, in channel-section guides *f* and, during the descent of the cars, in channel-section guides *g*.

Just at the period that the car, in its ascent, reaches the mouth *d*¹ of the chute, its skids *c*⁷ pass out of the guides *f* whereupon the weight of the passenger in the car causes the latter to tilt over in the direction of the arrow, Figure 4, and to discharge the passenger into the chute, the countersunk hole *b*² permitting of the consequent rocking movement of the pivot shaft *c*¹. As soon as the passenger is discharged, the springs *c*³ return the car to its normal vertical position, as shown in Figure 4, and in order to maintain the car in that position until it turns over for its return journey, and also until the skids enter the lower channel guide *g*, a pair of jockey wheels *h* is provided over, and in contact with which, the ends of the shaft *c*¹ ride.

Alternatively to the jockey wheels, any other suitable form of guides may be provided—for example, guide rails which are arranged between the upper ends of the channel guides *f* and *g* and between which the legs of the car pass. Upon the skids *c*⁷ leaving the guides *f*, the rear part of the car falls until the tie *c*⁵ engages the L-bar. The part of this tie which rests on the bar is cut away in the form of a V, as shown at *c*⁸, whereby undue movement of the rear part of the car is prevented.

As the car topples over about the pivot shaft *c*¹ as fulcrum, in order to commence its return downward journey, the rear part of the car, being free, will naturally tend to swing away from the conveyor. In order to prevent undue strain on the apparatus due to this movement of the car, the latter is controlled in any suitable way, for example, by means of a forwardly extending arm *j* fixed

to the car and provided with an upturned nose j^1 which engages the conveyor. In an alternative arrangement, shown in Figure 7, a check-plate k , is hinged at l to each of the 5 channel guides g and rests at its other end on a spring m supported by a portion of the staging a , a guide pin k^1 being fixed to the check-plate and passing freely through the part a . Thus, when the car reaches the limit of its 10 forward travel, it topples over in the direction of the downwardly-pointing straight arrow and its skids c^7 strike the check-plates, the shock being absorbed by the springs m . The check-plates then guide the skids into 15 the channel guides g . In the arrangement shown in Figure 8, the plate k and spring m are replaced by the laminated spring n .

Dealing now with the chute, Figure 9, its 20 sides d^1 are set back, as shown in Figure 9, so that passengers sitting on the sliding mat d^2 can avoid friction on their arms etc. and their clothing. Further, this absence of friction enables the passengers to attain greater speed down the chute.

25 Arranged at the lower end of each chute d and protruding therethrough are sets of rotary rubber or resilient tyred wheels o which are mounted on shafts o^1 and are driven in any suitable manner so that the 30 speed of rotation of the wheels nearest the chute is such as to check to some extent, but without discomfort, the speed of the passengers about to emerge from the chute. Each set of wheels onwards from the lower end of 35 the chute runs successively slower. The final set of wheels run at a speed which allows the passengers to alight without discomfort. It will be appreciated that these wheels serve to avoid congestion of passengers discharged 40 from the chute, as they act independently both of the weight of the passengers and the rate at which the chute discharges the passengers. Instead of wheels, drums provided with resilient peripheral ribs may be employed.

45 We claim:—

1. In an amusement device, a conveyor, cars, and L-bars connected to said conveyor and means connecting said cars to said L-bars, whereby the cars can swing in a plane at right angles to the direction of movement of the conveyor.
2. In an amusement device, a conveyor, cars, L-bars secured to the conveyor and each 55 having a hole in its web and shafts secured to the cars and passing freely through the holes in the said webs.
3. In an amusement device, a conveyor, cars, L-bars secured to the conveyor and each 60 having a hole in its web, shafts secured to the cars and passing freely through the holes in the said webs, and means for righting the cars from their tilted position.
4. In an amusement device, a conveyor, 65 cars, L-bars secured to the conveyor

and each having a hole in its web, shafts secured to the cars and passing freely through the holes in the said webs, and resilient means between the web and the car for righting the car from its tilted position.

5. In an amusement device, a conveyor, cars, L-bars secured to the conveyor and each having an oppositely countersunk hole in its web, and shafts secured to the cars and passing snugly through the holes in the said webs.

6. In an amusement device, a conveyor, cars, means for attaching the cars to the conveyor, projections on said cars, and means adapted to be engaged by said projections for keeping the cars in the non-tilted position during the period of their reversal of direction of travel.

7. In an amusement device, a conveyor, cars means for attaching the cars to the conveyor, projections on said cars and jockey wheels which are engaged by said projections and maintain the cars in their non-tilted position during the period of their reversal of direction of travel.

8. In an amusement device, a chain conveyor, cars attached to said conveyor, means for maintaining verticality of the cars during their ascent and descent, and means for maintaining verticality of the cars during the period of their reversal of direction of travel.

9. In an amusement device, a chain conveyor, cars attached to said conveyor, skids on the cars, channel-section members serving as guides for the skids, projections on the cars, and means arranged to be engaged by said projections to maintain verticality of the cars during the period of their reversal of direction of travel.

10. In an amusement device, a conveyor, cars attached to said conveyor, means for guiding the cars during their advance and return, and means for reducing the shock caused by the cars as they topple over to reverse their direction of travel.

11. In an amusement device, a conveyor, cars attached to said conveyor, a chute to receive the passengers discharged from said conveyor, and, at the discharge end of said chute rotatable elements to complete the discharge of the passengers from the chute.

In testimony whereof we have signed our names to this specification.

HAROLD PICKARD.
